UNITED STATES PATENT OFFICE.

WILLIAM S. KAPNEK, OF PHILADELPHIA, PENNSYLVANIA.

BOOTH CONSTRUCTION.

Application filed March 27, 1928. Serial No. 265,113.

My invention relates to booth construction. The object is to provide a simple and sanitary construction for booth compartments and the like.

5 The invention comprises improved means for forming the compartment walls and for securing the same in proper association.

Referring to the drawings which illustrate merely by way of example a suitable embodiment of the invention;

Fig. 1 is a front elevation.

Fig. 2 is a horizontal section of the arrangement shown in Fig. 1.

Fig. 3 is a perspective view of a vertical 15 T bar.

Fig. 4 is a fragmentary horizontal section on line 4, 4 of Fig. 1, on an enlarged scale.

Fig. 5 is a front elevation of a wall plate.

Fig. 6 is a top plan of same.

20 Fig. 7 is a top plan view of a tie-bar.

Fig. 8 is an end view of same.

Fig. 9 is a fragmentary side elevation of the end of the tie-bar with part of the T bar and connecting means in section.

25 Fig. 10 is a vertical section on line 10, 10 of Fig. 2.

Similar numerals refer to similar parts throughout the several views.

Referring especially to Figs. 2, 5, 6 and 30 7, the wall plates 17 are secured to the supporting wall 16 of the room by bolts 18 or other suitable means. These plates are each provided with a slot 19 having beveled edges 20 as shown in Fig. 6. A recess is usually

35 formed in the wall back of this slot for receiving the end of the tie-bar 21. This tie bar is provided with a number of dove-tailed formations 22, one of which is inserted in the slot 19. These wall plates and tie-bars 40 are spaced a short distance from the top and bottom of each compartment; the tie-bars extending horizontally to the front wall of the compartment. The front ends of the tie-bars are provided with the tapped or

45 threaded holes 23. At the front of the partition wall between two compartments is provided a T bar such as 24 shown in Fig. 3. The rear or inner web 25 of the T is cut away for a suitable space near the top and near the 50 bottom to receive the ends of the T bars.

Tapered recesses 26 are provided through the front face of the T bar where the web 25 is cut away for receiving the tapered nuts 27. Threaded rods 28 are secured in the holes 23 55 of the tie-bar 21. A lock nut 29 is then threaded onto the rod and the rod is then

inserted through the tapered openings 26 to receive the tapered nuts 27. These tapered nuts are tightened on the rods 28 until the T bar assumes the strictly vertical position and the lock nuts 29 are then moved into locking position. In this way is formed the frame of the several compartment partitions. Hinge lugs 30 are welded or otherwise secured to the vertical side edges of the T bar as shown 60 in Figs. 3 and 4, while a stop lug 31 is secured to the opposite vertical edge of the T bar also as shown in Figs. 3 and 4. On the ends of the lugs 30 are secured the slotted hinge blocks 32 as shown in Fig. 4. The 65 slot of the hinge block being such as to receive with a close fit the lug 30. The block and lug are then secured together by suitable screws or pins 33 and the outer face of the hinge block is suitably tapped for receiving 70 the screws 34 of the door hinge 35. On the stop lug 31 is secured the usual rubber cushion door stop 31'. The tops of the T bars 24 are secured together by the cross-bars 43. When the framework is thus assembled 75 80 sheets or panels 36 of sani onyx, glass or other similar material are provided of the exact dimension of the partition between the compartments. Upon the inner face of these panels are secured with a suitable cement 85 blocks 37 of wood or other suitable material of thickness corresponding to the thickness of the tie-bar 21. Two such panels are provided for flanking each set of tie-bars 21, and the blocks 37 are secured by cement or other suitable means, on the inner and adjacent faces of the panels 36. These blocks are staggered so that a block 37 on one panel will lie to one side of the block on the opposite panel. These blocks 37 are suitably positioned so that their lower ends will rest upon the top edge of the lower tie-bar 21 which thus supports the panels. Certain portions of the lower edges of the blocks 37 may be removed if desired to bring the panels 90 95 100 at the proper height above the floor level. Upon the balance of the adjacent inner faces of the panels are applied areas of cement 38 adapted for securing the adjacent faces of the panels together. These areas of cement must obviously be as thick or thicker than the tie rods which the panels flank. When the construction has progressed thus far, other panels such as 39 are secured to the rear wall against which the plates 17 are secured, and 105 narrow panels 40 and 41 are secured in a similar way at the front by cement or other

110

suitable means. The inner panels 40, for example, extend from the side panels 36, to the hinge on one side, and to the margin of the door opening on the other side. The outside 5 panels 41 extend from the hinge 35 to the edge of the door 42 of the adjacent compartment, as shown in Fig. 2. These plates or panels 40 and 41 are preferably recessed to receive the flanges of the T bar and also to 10 receive the hinge lugs 32 and stop elements 31, so that the remaining outer edges of the panels 40 and 41 may come together to make a neat finish as indicated in Fig. 2. Suitable 15 panels 43 are also provided to cover the cross bars 42'.

What I claim is:—

1. In a booth compartment structure, the combination of wall plates, tie-bars secured thereto and extending horizontally therefrom in spaced relationship, vertical T bars adjustably secured to the outer ends of the tie-bars, and panel plates secured in vertical planes flanking the tie-bars.

2. In a booth compartment structure, the combination of wall plates, tie-bars secured thereto and extending horizontally therefrom in spaced relationship, vertical T bars adjustably secured to the outer ends of the tie-bars, and panel plates secured in vertical planes flanking the tie-bars and provided with blocks secured between the plates for resting upon a tie-bar.

3. In a booth compartment structure, the combination of wall plates, tie-bars adjustably secured thereto and extending horizontally therefrom in spaced relationship, vertical T bars adjustably secured to the outer ends of the tie-bars, and panel plates secured in vertical planes flanking the tie-bars.

4. In a booth compartment structure, the combination of wall plates provided with slots having beveled edges, tie-bars provided with a series of dove-tail formations for adjustable engagement with said slots and extending horizontally therefrom in spaced relationship, vertical T bars adjustably secured to the outer ends of the tie-bars, and panel plates secured in vertical planes flanking the tie-bars.

5. In a booth compartment structure, the combination of wall plates, tie-bars secured thereto and extending horizontally therefrom in spaced relationship, vertical T bars adjustably secured to the outer ends of the tie-bars by means of bolts, nuts and lock nuts, 55 and panel plates secured in vertical planes flanking the tie-bars.

6. In a booth compartment structure, the combination of wall plates, tie-bars secured thereto and extending horizontally therefrom in spaced relationship, vertical T bars adjustably secured to the outer ends of the tie-bars, and panel plates secured in vertical planes flanking the tie-bars, said T bars provided with lugs and hinge blocks secured to 60 the lugs.

7. In a booth compartment structure, the combination of wall plates, tie-bars secured thereto and extending horizontally therefrom in spaced relationship, vertical T bars 70 secured to the outer ends of the tie-bars, and panel plates secured in vertical planes flanking the tie-bars, said T bars having lugs welded to the webs thereof for association with hinges and door stops.

8. In a booth compartment structure, the combination of wall plates, tie-bars secured thereto and extending horizontally therefrom in spaced relationship, vertical T bars adjustably secured to the outer ends of the tie-bars, and panel plates secured in vertical planes flanking the tie-bars and other plates 80 for covering other exposed parts.

9. In a booth compartment structure, the combination of horizontally extending bars 85 in spaced relationship, means for connecting said bars as to one end with a supporting wall, vertical bars connected to and supporting the horizontal bars as to the other end, panel plates flanking the horizontal bars and 90 having their adjacent sides secured together, blocks secured to adjacent sides of the flanking plates in staggered relationship, and adapted to rest upon a horizontal bar, and other flanking panel plates having recesses 95 for receiving certain of the metal parts.

WILLIAM S. KAPNEK.
